UNITED STATES PATENT OFFICE.

ALBERT WATKINSON, OF KYNETON, AUSTRALIA.

INDICATOR MEANS FOR USE ON RECREATION-GROUNDS OR RACE-COURSES.

1,393,414.

Specification of Letters Patent. Patented Oct. 11, 1921.

Application filed November 3, 1919. Serial No. 335,458.

To all whom it may concern:

Be it known that I, ALBERT WATKINSON, a subject of the King of Great Britain, residing at Kyneton, in the State of Victoria, 5 Australia, have invented certain new and useful Improvements in Indicator Means for use in Recreation Grounds or Race-Courses, of which the following is a specification.

The present invention refers to boards 10 erected on recreation grounds for the purpose of providing visible notices to the public regarding the events to be contested and consists principally in indicating the distinctive number of the starters and when 15 used in connection with horse races, means are provided, registering opposite each of said numbers, for exhibiting the name of the respective jockey and other information desired by the patrons of the sport. Other 20 notices than those mentioned may also be displayed in special places on the board as for instance results, time occupied by each race, the number of the race, starting time and, when the event is over, signs are ex- 25 hibited regarding correctness of weight, protests and decisions or appeals thereon. In addition, general notices may be exhibited as for instance a request for attendance of a medical practitioner. Furthermore a 30 portion of the board which is preferable arranged in advance of the main portion of the board is utilized to show, during the time occupied over the sports, the scratchings of contestants as regards all the events 35 of a program and the results of each event.

Briefly stated the essential structural feature of the indicator board according to this invention consists in the use of vertically operable counterweighted plates bearing 40 numbers or the like controlled from a distance as by flexible connecting means attached thereto such as a chain or cord passing over a guide pulley or pulleys to the manual control position. These plates 45 move downwardly into and upwardly out of pockets formed in the face of the board and when required as for horse racing may be associated with extended panels with means for attaching notices to same such as a 50 jockey's name.

In the preferred form the main portion of the board, that displays the information relating to a particular event, is arranged with

a plurality of lines of quincuncially arranged or horizontally staggered pockets 55 or cells each to contain one of the before mentioned number-plates. The pockets are of rectangular form each having its bottom edge sloping downwardly and outwardly to form an outward runway for rain water. 60

The top of the pocket is slotted or otherwise arranged for the entrance and withdrawal in a vertical plane of the counterweighted number plate which when in the withdrawn and raised position is completely 65 housed behind the face of the board. The back of the board is closed preferably by sheets of corrugated iron which can be readily removed if interior inspection or adjustment is required. 70

Where one pocket is to be used for displaying different notices, as at the top of the board, each of the notice plates would be arranged one behind the other and separately controlled. 75

The control or operative means for the display plates may be assembled in convenient position at the rear or front of the board at its base and each would bear an indication corresponding to the plate which it controls. Automatic means are also provided for dropping into view in consecutive order any number of number plates and immediately afterward recording scratchings. 80

Arranged closely adjacent to each vertical 85 line of pockets, in the case of a board used for horse race meetings, is a suitably guided vertical panel extending the full vertical height of said line, and if required below the lowermost number plate. This panel is also 90 counterweighted and capable of being drawn downwardly for the purpose of attaching jockey's name plates thereon. This attachment can conveniently be effected by providing on the face of the panel flanged or channeled containers or bent lugs each adapted to register opposite a pocket when the panel is raised. The plate is slipped into the retaining device with portion of same projecting beyond and overlying the 95 blank space provided therefor on the board consequent upon the staggered arrangement of the number pockets. 100

A similar extended panel may be provided at each side of the board on which results 105 and time or notices of a general character

may be exhibited, or a comparatively wide vertically sliding panel may be employed.

To provide that the whole of the independent panels carrying the jockey's names 5 can be lowered or raised simultaneously I may couple the same together by a cross bar connected to a winch located at the ground or other convenient level, or by a preferred arrangement all the panels are permanently 10 fixed to a vertically slidable guided frame.

The "all-events" portion of the board provided with means for displaying the scratchings and results of all events of a program may be arranged at each side of the "single-event" portion of the board or immediately 15 below same but as previously stated it is preferably detached and erected in front of the lower or unused portion of the main board. On account of economy of space the 20 number plates preferably slide horizontally into or out of pockets and can be attended to by the man operating the panels.

The above description defines the essential characteristics of the present invention, 25 practical embodiments of which are depicted in the attached sheets of drawings.

In these drawings—

Figure 1 is a front elevation of one arrangement of the main portion of the board;

Fig. 19 is a detail view illustrating the operation of the scratching traveler;

Fig. 20 is a diagrammatic view illustrating the means for operating at a convenient position behind the board, the hands of the 70 starting-time indicator erected at the top of the single event scratching board;

Fig. 21 is a plan view of Fig. 20. Fig. 22 is a fragmentary view of a guide bearing shown in Figs. 9, 16, 17 and 18. 75

In the drawings (a) and (b) designate the front and rear sides of the structure (Fig. 3) which is partitioned longitudinally the number of such partitions corresponding to the number of vertical lines of pockets 80 (d) in the front of the structure. These partitions are divided transversely to form a separate housing (e) for each number plate (f). The front face and pockets are preferably constructed of sheet metal for 85 rendering the structure watertight and the bottom of each pocket is sloped downwardly and outwardly as shown in Fig. 3 being supported upon a wooden plate (g) on the under surface of which is attached the pulleys (g¹) over which passes the operating 90 chain or wire (g²) of the next lower number plate.

The plates (f) are counterweighted at the bottom edge (f¹) and the chain or other 95 flexible connection (g²) is attached to the rear of same, from which after passing over the pulleys (g¹) they are carried to the control position as for instance at the basal portion (g³) of the structure (see Fig. 3). 100 A convenient means for use in operating the plates is shown in Figs. 9, 16, 17 and 18 which illustrate an extended bolt (g⁴) two of which are shown in Fig. 9 the one on the left hand side being in the lowered position 105 when its corresponding number plate would be raised and obscured in its particular housing, and the other bolt in the opposite or raised position when the associated plate is visible in its pocket on the board. The 110 curved finger piece (g⁵) on each of said bolts engages under a stop piece (g⁶) when in the raised position and when lowered the bolt or rod g⁴ is partially rotated to cause the finger piece g⁵ to register in a notch g⁷ formed in 115 the edge of guides g²⁰ provided for the bolts as in Figs. 9 and 22. Upon each of the stops g⁶ a plate g⁸ is provided bearing an indication corresponding to the number plate controlled by the bolt g⁴. 120

In order to drop all the number plates of the main board into view it is necessary, according to the construction described, to release by hand each finger piece (g⁵) from its respective notch (g⁷). This operation however may be conveniently carried out automatically by the means illustrated in Figs. 16, 17, 18 and 19.

In this construction a T-section guide rail (m) is mounted horizontally close to and 130

slightly below the notches (g^7) and upon said rail is mounted a flanged slide (m^1) provided with a traction cord (m^2) passed over one or more pulleys (m^3) and operated by a weight (m^4). When drawn back into operating position the slide is retained by a suitable catch such as a pin (m^5) dropped into a hole formed in the rail (m) and when released the slide abuts against a removable stop (m^6) placed in one or other of a series of holes (m^7) formed in the guide rail.

Upon the slide, an arm (m^8) is mounted on a pivot (m^9) said arm having a laterally and upwardly projecting lug (m^{10}) curved 15 on one edge as illustrated. The arm is normally held stationary on the slide as for instance by means of an offset (m^{11}) provided with a pin (m^{12}) that fits in a hole formed in the slide. The finger pieces (g^5) 20 which are preferably curved slightly are when retained in the notches (g^7) formed in the semi-circular guide bearings (g^{20}) projecting in the path of travel of the lug (m^{10}) so that when the pin (m^5) is released 25 said lug during the travel of the slide by reason of the weight (m^4) along the rail, successively releases the finger pieces g^5 from the notches (g^7) and causes the required number or indicator plates (f) to drop into 30 view in the pockets (d) in consecutive order.

It will be understood that the stop pin (m^6) is moved into one or other of the holes (m^7) according to the number of entrants of an event.

35 In order to return the slide to starting position without interfering with subsequently lowered finger pieces (g^5) the offset (m^{11}) is lifted sufficiently to release the pin (m^{12}) and the arm (m^8) swung on its pivot (m^9) as indicated in broken lines Fig. 17.

Operating in conjunction with the just described automatic mechanism for displaying the number plates of the entrants of an event, means are provided for immediately 45 recording the scratchings. This consists of a scratching slide (s) Figs. 16, 17 and 19 flanged to engage and travel when released along the rail (m) after the slide (m^1) has performed its function. The scratching 50 slide when released from a retaining catch (s^{15}) travels through the medium of a cord or the like (s^1) attached to said slide passing over one or more pulleys and operated by a weight s^2 . Projecting downwardly 55 from one side of the scratching slide is a plate (s^3) provided with an inwardly projecting horizontal cam (s^4) with its forward edge inclined to the line of travel, said plate being hinged at (s^5) to the slide and normally secured in operating position by a pin (s^6) or other fastening device.

60 Fixed to the rail (m) opposite each operating bolt (g^4) of the display plates (f) is a vertically disposed bent wire support (s^7) curved downwardly as at (s^{12}) toward

its free end, said support being used for the suspension therefrom of a weight (s^8) having an elongated looped shank (s^9) which is threaded on the support (s^7) till it comes to rest on the horizontal seating portion thereof as illustrated in Fig. 19.

65 Each bolt (g^4) is formed at its lower extremity with a hook (s^{11}) so that when the scratching slide (s) advances along the rail (m) its inclined cam (s^4) strikes the shank (s^9) of the weight and causes it to slide down the curved portion s^{12} of the bent wire support and drop on the hook (s^{11}). Thus the weight (s^8) is transferred to the bolt g^4 and being made heavier than the display plate (f) with which it is associated, the flexible connection g^2 is pulled and said plate rises from its pocket into an unexposed position thus indicating a scratched entrant.

70 It will be understood with the foregoing automatic control mechanism described and illustrated in Figs. 16, 17, 18 and 19, the release and travel of first operating slide 75 (m^1) causes all the required display plates 80 to be consecutively dropped into view in the pockets and immediately afterward the scratching slide (s) follows along the guide rail and by contact with the shanks of 85 weights (s^8) hung on the supports (s^7), causes the bolts (g^4) corresponding with the weights (s^8) to be drawn down and thus obscure the respective number or indicator plate. The operation of setting the number 90 plate and indicating scratchings on the board occupies but a few seconds and is thus 95 more expeditious than the manual release by the finger pieces (g^5).

100 As most of the scratchings are known some time before an event the operator has abundance of time to set the scratching weights (s^8) on the supports corresponding with the number plates of scratched entrants of an event.

105 According to one convenient arrangement 110 the slide (m^1) may be utilized when at the end of its travel to release the scratching slide (s) and accordingly a wire rod (m^{13}) is supported in guides along the rail (m) and provided with a stop (s^{16}) placed adjacent the stop (m^6) and adapted to be engaged by the forward end of the setting slide (m^1) when terminating its travel. The other end of the wire rod is similarly formed 115 and a projection (s^{14}) which when the rod 120 is slid forwardly contacts with and releases a bevel pivoted catch (s^{15}) from engagement with the scratching slide (s) thereby allowing the latter to travel along the rail 125 and perform its function.

130 In order to return the slide (s) its side plate (s^3) is released and swung on its pivot (s^5).

It will be evident that although weights are employed as the simplest device to draw

the slides along the rail the same object may be accomplished by other mechanism or manually by drawing the traction cords. Furthermore it will be evident that either one or the other of the slides and its associated elements may be dispensed with if preferred in which case one of the two distinct operations would be carried out manually.

10 Referring to Figs. 3 and 5 the means for guiding the number plate (f) consist of suitably fixed parallel rods f^{11} on which run the eyes f^2 attached to the rear face of the plates. The side edges of the plates may 15 also be arranged to run in guide strips f^3 .

The vertical panels (p) arranged between the vertical lines of the pockets (d) and one at each side of the board extend from the top to the lowest line of pockets.

20 A weather hood (p¹) is affixed to the face of the board to cover the top of each of the panels when in the normal or raised position.

The details of construction of the independent panels (p) are clearly shown in 25 Figs. 6, 7 and 8.

The panel consists of longitudinal slats (p²) braced by rearwardly disposed straps (k) channel shaped as shown in Fig. 7, 30 and to which slats are affixed the containers (p³) formed of a flat strip bent over at the top and bottom edges and at one end as shown to form grooves to receive a sheath (p⁴) for an indicator or display plate (p⁵).

35 The transverse distance between said edges is greater than the width of the sheath p^4 and in the groove formed at the top edge of the container (p³) is fitted a downwardly curved leaf spring (p⁶) which bears upon the top edge of the sheath (p⁴) and retains same level (see Fig. 6). The panel (p) is guided by pipes p^7 located one at each side of same and fixed to a bearer p^8 attached to the backing plate p^9 (see Figs. 6 and 7).

40 The panels (p) are each connected at the top to a wire or chain (p¹⁰) passing over a pulley (p¹⁰) dependent from the frame member (p¹¹) of the board (see Fig. 4) said wire being connected to a terminal counter-weight (p¹²).

45 The panel (p) located at the left side of the board (Fig. 1) is used for displaying notices of a general character to register over the underlying blank space at the extreme left of the board and the containers (p³) of such panel are reversed as the display or indicator plates (p⁵) project from the left side thereof.

50 Where several indicator plates are used at one pocket opening as shown at the top of the board (Figs. 1 and 4) the pulleys over which their suspension wires run may be arranged on a common spindle (d').

55 Each of the containers (p³) bears on its face (see Fig. 1) an indication correspond-

ing to the number plate against which it registers so that when the panel (p) is lowered there will be no difficulty in determining into which container a particular plate (p⁵) should be inserted.

70 The panels (p) may be operated independently or simultaneously from the bottom ends by connecting together the slats (p²) (see Fig. 10) by a readily removable cross bar (p¹³) to which is attached a divided pull rope or wire (p¹⁴) to the junction of which is attached a wire passing to a hand actuated winch (p¹⁵) (Fig. 4) contained in a housing (p¹⁶) at the rear of the board.

75 As a permanent arrangement and according to the preferred form of the invention the panels (p) may be fixed in a frame (p²⁴) Figs. 11 and 12 to slide in guides (p⁴⁴) up and down the face (a) of the main board the rope or wire (p¹⁴) being connected to the top of the frame and passing over a pulley (p²⁵) and connected with the winch (p¹⁵) (Fig. 4). Ropes (p²⁶) attached to the top of the frame pass over 80 pulleys (p²⁷) and are provided at their ends with weights to partially counterbalance the weight of the frame.

85 By means of this construction the whole frame can be lowered out of sight of the public behind a screen or the detached "all-events" portion of the scratching board arranged as in Fig. 12. Thus the display plates may be fitted to the panels out of 90 view of the public and subsequently raised or retained in lowered position if not required as in pedestrian sports. Moreover indicator plates (p⁵) of considerably greater length may be employed than is the case in the form of the invention shown in Fig. 1 95 and consequently apart from jockeys' names the plates may contain further information desired by the public such as, starting position, weight allowance, penalty weight and over weight. In addition one vertically 100 sliding side panel (p²⁸) may be independent of the frame (p²⁴) and wider than the left hand side panel shown in Fig. 1 and utilized for fixing thereto plates (p⁵) exhibiting 105 special notices between races and the numbers of placed competitors of the race and the time immediately after the event.

110 The indicator preferably incorporates means for exhibiting the scratchings for all events and the results of the latter and for 115 this purpose the board is either extended in any direction to provide space for this information or this portion of the indicator means may be provided by the erection of an "all-events" scratching board a few feet 120 in advance of the "single-event" scratching board as illustrated in Figs. 11-15 of the drawings. The objects of separating the 125 two portions of the board are that the person operating the panels may also operate 130

the "all-events" board and the operator is obscured from view during this work. This "all-events" board (*w*) is suitably framed and formed with a panel (*w*¹) for each 5 event and each panel contains vertical rows of slide plates (*w*²) numerically marked, each mounted to slide into or out of an exposed position and be concealed when not required in a pocket (*w*³).

10 In the practical construction as illustrated in Figs. 13-15 the plates are provided on their back with studs (*w*⁴) which project through horizontal guide slots (*w*⁵) formed in the back plate (*w*⁶) of the board, said 15 studs being riveted to the flanges (*w*⁷) of a finger grip (*w*⁸) provided for the manipulation of the slide plates (*w*²). Below each panel (*w*¹) an opening (*w*⁹) is formed (Fig. 11) which is fitted with a plate (*w*¹⁰) to exhibit the numbers of the placed horses of 20 the respective events and the time taken.

Figs. 20 and 21 show convenient means for operating at a distance the hands of the clock-faced dial (*t*) elevated on the board 25 and used for indicating the starting time of an event. As illustrated a duplicate (*t*¹) of the dial (*t*) is located at a convenient position at the rear of the main board and faced in opposite direction to the indicator dial 30 (*t*). The minute and hour hands on each dial are fixed respectively to separate spindles (*t*²) (*t*³), and (*t*⁴) (*t*⁵) provided with pulleys (*t*⁶) (*t*⁷), (*t*⁸) (*t*⁹). Crossed endless cords or belts (*t*¹⁰) (*t*¹¹) from pulleys 35 *t*⁶ *t*⁷ pass around pulleys (*t*¹²) (*t*⁸) and fixed on the spindles of the latter are pulleys (*t*¹⁴) (*t*¹⁵) connected by endless cords (*t*¹⁶) (*t*¹⁷) respectively with the pulleys (*t*⁹) and (*t*⁸). Thus by rotating the hands of the device 40 (*t*¹) to show a particular time, the hands of the starting time indicator on the face of the board near the top thereof are correspondingly altered.

It is to be clearly understood that I do 45 not restrict myself to the particular practical forms and details of construction above described with reference to the accompanying drawings as modifications of such means and arrangements can be made within the 50 scope of the present invention.

Having now particularly described and ascertained the nature of my said invention, and in what manner the same is to be performed, I declare that what I claim is:

55 1. In an indicator, the combination with a frame divided into rows of separate divisions and each division having pockets provided with an exposure opening; of indicator plates housed from view in said 60 pockets above said opening; counterweighted flexible means for each plate, and means

for holding said plates in raised position concealed above the exposure opening.

2. In an indicator, the combination with a frame divided into vertical rows of separate 65 divisions and each division including an open-faced pocket; of a gravity-actuated indicator plate for each pocket, counterweighted flexible actuating means for each plate, and a latching device for each of said means to normally hold the plate concealed behind said frame above its pocket and means to automatically release all of the latches.

3. In an indicator, the combination with a 70 frame divided into vertical rows of separate divisions and each division including an open-faced pocket; of a gravity actuated indicator plate for each pocket, counterweighted flexible actuating means for each plate, and a latching device for each of said 75 means to normally hold the plate concealed behind the frame above its pocket, means to automatically release all of the latches, and means for automatically raising one or more 80 of the dropped plates.

4. In an indicator, the combination with a frame divided into vertical rows of separate 85 divisions and each division including an open-faced pocket; of a gravity operated indicator plate for each division, a flexible actuating rod for each plate terminating in a hook, a rail extending across the bars, removable weights, supports for said weights, one adjacent each hook, and means 90 slidable on said bar to transfer weights on the supports to the respective hooks.

5. In an indicator, the combination with a 95 frame having divisions quincuncially arranged, each division including an open-faced pocket, vertical panels between the vertical rows of divisions, plate holders slideable in said panels, flexible means for raising said holders, panels in said plate holders projecting over the space between divisions 100 of a vertical row of divisions on one side of a panel and in alignment with a pocket on the other side of said panel.

6. In an indicator, the combination with a frame divided into vertical rows of separate 105 divisions having pockets provided with exposure openings; of indicator plates housed in said pockets above the exposure openings, counterweighted flexible means for each plate, means for holding said plates in raised 110 position, and vertically movable name carriers alternating with said vertical rows of pockets and movable in relation to various exposure openings of said rows.

Dated this 25th day of August, A. D. 1919. 120

ALBERT WATKINSON.
